Jan. 31, 1961

G. M. SNYDER

2,969,625

G. M. SNYDER
CONTROL ACTUATING MEANS FOR MACHINE ELEMENT
HAVING A VARIABLE ZONE OF MOVEMENT
Filed Jan. 9, 1959

Filed Jan. 9, 1959

support slidably mounted thereon for movement toward and from operative position, a grinding wheel on said grinding wheel support, spaced control members positioned to correspond to the advanced and retracted positions of said grinding wheel support, means movable with said grinding wheel support for actuating said control members, means to advance said grinding wheel support to compensate for wheel wear and means to prevent a corresponding advance of said control member actuating means comprising a magnet for slidably attaching said actuating means to said grinding wheel support and adjustable stops for limiting the movement of said actuating means in both directions

10

5 References Cited in the file of this patent

UNITED STATES PATENTS

456,553	Carr	July 28, 1891
2,075,369	Stetler	Mar. 30, 1937
2,704,890	Welsch	Mar. 29, 1955